UNITED STATES PATENT OFFICE.

HENRY L. FERRIS, OF HARVARD, ILLINOIS, ASSIGNOR TO HUNT, HELM, FERRIS & COMPANY, A CORPORATION OF ILLINOIS.

FEED AND LITTER CARRIER.

No. 884,649.

Specification of Letters Patent.

Patented April 14, 1908.

Application filed March 18, 1907. Serial No. 362,990.

To all whom it may concern:

Be it known that I, HENRY L. FERRIS, a citizen of the United States, residing at Harvard, in the county of McHenry and State of Illinois, have invented a new and useful Feed and Litter Carrier, of which the following is a specification.

My invention relates to certain new and useful improvements in feed and litter carriers, and is fully described and explained in the specification and shown in the accompanying drawings, in which

Figure 1 is an elevation of my improved device showing the same in position upon a track; Fig. 2 is a central longitudinal section through one of the hangers and parts adjacent thereto; Fig. 3 is an end view of the parts shown in Fig. 2, looking from the left as seen in Fig. 2; Fig. 4 is a perspective view of the switching mechanism together with a portion of the movable switch track; Fig. 5 is a plan of the tracks, the switching mechanism being cut off in horizontal section just above the level of one of the tracks; and Fig. 6 is a section in the line 6 of Fig. 5 showing the pivot of the movable switch track.

Referring to the drawings, A is a suitable track which in the form of construction herein illustrated is composed of two angle irons, 30 with the angles at the lower adjacent corners, bolted together so as to form two substantially horizontal webs and an upwardly extending central slotted portion. Upon the track, A, run pulleys, b, arranged in pairs 35 running upon the two horizontal webs of the track, the said pulleys being secured in position in hangers, B, which may be of any desired form and are suitable for surrounding track, A. Swiveled to the hangers, B, are 40 journals, C, C', between which extends a rotatable shaft, D, preferably constructed of tubing for the sake of strength and lightness. On one end of the shaft, D, I mount a gear, E, freely rotatable with respect to the shaft 45 and held against longitudinal displacement thereon by engagement with the hanger, C, to one side and with a pin, e, running in an annular groove upon the gear to the other side, the pin being securely fastened to the 50 shaft as indicated in Fig. 2. The gear, E, meshes with a worm, E¹, secured to a counter-shaft, e¹, extending transversely with respect to the shaft D, and journaled in suitable brackets provided to receive it upon the 55 hanger, C. To one end of the shaft, e¹, is

secured a sheave, F, over which runs a continuous loop of chain or other flexible material, F¹. It will be obvious that by drawing the loop, F¹, continuously in one direction, the sheave, F, will be rotated, with consequent rotation of the gear, E, through the medium of the worm, E¹. Reverse action, i. e. rotation of the sheave by pressure exerted upon the gear is readily prevented by properly arranging the pitch of the worm and gear.

In order to secure a rotation of the shaft, D, when the gear, E, is rotated, I secure to the shaft, D, a longitudinally movable clutch-collar, G, secured against rotation with respect to the shaft by means of a pin, g, passing through a slot in the shaft. The face of the clutch-collar adjacent to the gear, E, is formed with projections adapted to engage with corresponding depressions in the face of the gear all formed in the ordinary way common in such devices. Pivoted to the bracket in which the worm, E¹, is journaled, is a bell-crank lever, G¹, having a horizontal arm and a vertical arm, the horizontal arm having secured to its extremity a chain, g¹, by which the bell-crank lever can be rotated. The vertical arm of the bell-crank is bifurcated and carries upon its upper end pins, which run in an annular groove upon the clutch-collar, G. The bell-crank lever, G¹, is normally held, by means of a spring, g², in such position as to hold the clutch-collar, G, in engagement with the gear, E, so that the shaft and gear will normally rotate together, but the shaft can be disengaged from the gear at any time by drawing down upon the chain, g¹. As a matter of convenience, I utilize the chain, g¹, as an anchoring chain and for this purpose I secure to it an anchoring hook, g³, which can engage with one of the webs of the track and when in such engagement will prevent longitudinal movement of the carrier along the track, any pressure exerted by the carrier upon the bell-crank lever at such times being a horizontal or substantially horizontal pull which will not tend to rotate the bell-crank and disengage the clutch.

H indicates the container of my improved carrier, the same being pivotally supported in unstable equilibrium in an inverted U-shaped frame, H¹, the usual locking means for the container being provided at one end as illustrated in Fig. 1.

As far as my present invention is con-

cerned, any form of locking and tripping mechanism may be used and I therefore do not describe it particularly, although the form herein illustrated is that shown and described and claimed in my application filed on even date herewith and allotted Serial No. 362,989.

The frame, H^1 , has at its upper corner two pulleys, h . Chains, I , I^1 , run over these pulleys, the chain I , being fastened to an eye, i , fast upon the shaft, D , at one end and having its opposite end secured to a collar, i^1 , rotatable upon the said shaft but held against longitudinal movement thereon, and the chain, I^1 , having one end stationarily secured to an eye, i^2 , upon the shaft D , and having its opposite end secured to an eye in the journal, C^1 . Thus when the shaft, D , is rotated by the means already described, the two right hand ends of the chain, I and I^1 , will be wound up upon said shaft so that the frame, H^1 , and container, H , will be raised. When raised these parts will stay in any desired position by reason of the use of the worm and gear as one of the elements of the hoisting means and the same can readily be lowered by throwing out the clutch to permit the shaft to rotate in a reverse direction. The right hand ends or links of the chain will not be wound up so that the shaft will have a double leverage upon the container.

Referring more particularly to Figs. 4, 5 and 6, I will set forth the construction of the switching mechanism used in connection with my carrier. Between the two angle arm members of the track, A , at the ends where it is desired to switch the carriers, is secured a bracket, a , bifurcated at its end, a pin, a^1 , being passed vertically through the furcations of said bracket. Pivotal secured to said pin, a^1 , is a second bracket, a^2 , secured between the ends of two corresponding angle-iron members of a switch track, A^1 , the perforations through said bracket, a^2 , being enlarged at its upper end so that said switch track may be swung vertically about its pivot to a slight extent as well as horizontally.

In the form of device illustrated in the drawings, three terminal tracks, A^2 , A^3 and A^4 are provided, the ends of said terminal tracks being arranged on an arc struck about the pin, a^1 , as a center, so that the free end of the switch track, A^1 , can be brought into immediate juxtaposition with any one of the terminal tracks as desired.

A latch, J , is secured to the free end of the switch track, A^1 , and said latch has a downwardly projecting point, j , adapted to pass between the members of the terminal tracks, A^2 , A^3 and A^4 , to lock the switch track in alinement with any one of said tracks as may be desired. The upper end of the latch, J , is provided with a hook, j^1 , adapted to engage with notches, k , in a segment, k^1 , car-

ried by a switch bracket, K , supported above the terminal tracks by posts attached thereto. The switch bracket, K , is provided with pulleys, k^2 , and a cord, K^1 , runs over said pulleys, k^2 , and is secured to the latch, J , well below the level of said pulleys. When it is desired to shift the switch track, all that it is necessary to do is to pull downward upon the free ends of the cord, K^1 , so as to tighten the length between the pulleys, k^2 , thereby raising the latch, J , and the free end of the switch track, A^1 , to such an extent that the downwardly projecting point, j , upon the latch, J , is disengaged from the terminal tracks, A^2 , A^3 and A^4 . By pulling upon one end of the cord and mean-while keeping tension upon the other end thereof the free end of the switch track can be shifted as desired and brought into alinement with any one of the terminal tracks, and upon releasing the cord the track will be properly alined by engagement of the hook and point upon the latch with the notches upon the segment and with the terminal tracks respectively. The switching operation can be effected with the greatest ease and the proper alinement of the tracks is largely automatic, because, in practice, as soon as the hook upon the latch has ridden up upon the segment out of one notch, it will be permitted to rest thereon, and will be drawn along by one end of the cord, and upon reaching the next succeeding notch, the switch track will fall automatically into place in proper and perfect alinement.

In this application I have drawn claims only to the overhead switch portion of the device above described and the parts properly combined therewith, all claims to the container itself and the hoisting means therefor being embodied in an application filed on the 11th day of December 1907, Serial No. 406015 which application shows a container substantially similar to the one shown in this application but with a certain improvement added thereto.

I realize that considerable variation is possible in the details of this construction without departing from the spirit of my invention, and I do not intend therefore to limit myself to the specific form herein shown and described.

I claim as new and desire to secure by Letters Patent:

1. The combination with a main track, A , hangers running upon said track and a container carried by said hangers, of a pivoted switch track, cord guides adjacent to the free ends of such switch track, a cord passing over said cord guides and having engagement with the free end of said switch track and engaging means on the switch-track to coöperate with the terminal tracks to aline the switch-track therewith.
2. The combination with a main track,

hangers running upon said main track and a container carried by said hangers, of terminal tracks, a switch track pivoted to the end of said main track, and capable of a limited vertical movement about its pivot, 5 cord guides adjacent to the free end of such switch track and above the same, cords passing over said guides and having engagement with said switch track below said guides, 10 and engaging means on said switch track to coöperate with said terminal tracks.

3. The combination with a main track, hangers running thereon and a container carried by said hangers, of terminal tracks, 15 a pivoted switch track secured to the end of said main track and capable of a slight vertical oscillation about its pivot in addition to a horizontal movement, a latch on the end of said switch track having a point adapted 20 to engage the terminal tracks, cord guides adjacent to and above the end of said switch track, and cords passing over said guides and engaging said switch track below said guides.

25 4. The combination with a main track, hangers running upon said main track and a container carried by said hangers, of terminal tracks, a switch track pivoted to the end of said main track and capable of horizontal oscillation about its pivot and a limited vertical oscillation, a latch on the end 30

of said switch track, a hook on said latch, a segment having notches for engagement with said hook, cord guides adjacent to the free end of said switch and above the same, 35 and cords passing through said cord guides and having engagement with said latch below said guides.

5. The combination with a main track, hangers running upon said track and a container carried by said hangers, of terminal tracks, a switch track pivoted to the end of the main track and capable of horizontal oscillation about its pivot and a limited vertical oscillation, a latch on the end of said 40 switch track having a point to engage with the terminal tracks, a hook on said latch, a segment having notches to engage with said hook, cord guides adjacent to the end of said switch track and above the same and cords 45 passing over said cord guides and having engagement with said latch below the level of said guides.

In testimony whereof I have hereunto set my hand in the presence of two subscribing 55 witnesses, at Chicago, Illinois, this sixteenth day of March, A. D. 1907.

HENRY J. FERRIS.
